John Sheets

United States Patent Office.

JOHN SHEETS, OF COLUMBIA, PENNSYLVANIA.

Letters Patent No. 75,989, dated March 24, 1868.

IMPROVEMENT IN SAND-SCOOPS.

The Schedule referred to in these Letters Patent and making part of the same.

TO ALL WHOM IT MAY CONCERN:

Be it known that I, JOHN SHEETS, of Columbia, in the county of Lancaster, and State of Pennsylvania, have invented a new and useful Scoop and Appliances for Raising Sand from the River-Bed on to a Boat and the like; and I do hereby declare that the following is a full, clear, and exact description of the construction and operation of the same, reference being had to the accompanying drawings, making a part of this specification, in which—

Figure 1 is a perspective view of the scoop and appliances attached.

Figure 2, the same on a smaller scale, illustrating its operation in part.

The nature of my invention consists in providing a long-handled scoop and appliances, to enable me to raise sand from the bottom of a river-bed or stream, where the water is too deep to wade in, and raise it with an ordinary shovel, as is the usual practice for procuring the sand, so much used for building purposes.

To enable others skilled in the art to make and use my invention, I will proceed to describe its construction and operation.

Fig. 1 shows my scoop, made of stout sheet iron or light boiler-iron, say, bottom A, sixteen inches square, hind rim, C, raised up in a line perpendicular to the base, six inches, the sides, B B', rounded off to the front edge. A socket for a handle, H, is affixed centrally to the rear end C, on the inside, the handle, say eight feet long, fashioned above at H, like the handle of a spade or plane. At D, there is a shoulder left in the wood, or set on, and a ring, E, with a hook or ring through the united, and raised ends, for the attachment of a rope, G. There are also a pair of braces, F F, shown, made in a continuous piece, of stout round iron wire, which is affixed on each side, to the forward portion of the raised sides B. The cord G is provided with a series of links, L, as shown.

The manner of using this scoop is as follows: The boat used being usually what is termed "flat-bottom." This is anchored over the bed of sand, a stout spike is firmly driven in at a suitable point on the boat, for the purpose of holding the rope, by one of its links being thrown over it, so that when the scoop is thrust down into the sand, the portion of rope from the ring on the handle is stretched, and, forming a brace or fulcrum for the leverage of the handle, which is pushed out and the scoop filled, and the rope is then used to aid in raising the same, and the ring E allows the scoop to be turned, so that shoulder D on the handle is lodged upon the edge of the boat, and forms a rest or fulcrum for turning the scoop inwards, and discharging its contents into the boat. Thus, by this method, I have raised sand in one day, with comparative ease, that yielded me sixteen dollars, whereas by the method universally in use here, (or elsewhere, as far as I know,) it was a hard day's work to earn five dollars.

I am aware that the device may seem very simple, and offers no special novelty in its parts, separately considered, but in the application it has proved an efficient invention, of which others are very ready to avail themselves.

What I claim as my invention, and desire to secure by Letters Patent, is—

The arrangement of the socket, scoop, and handle H, with its shoulder D, ring E, braces F F, in combination with the rope, or its equivalent, and links L, when made substantially in the manner and for the purpose specified:
